UNITED STATES PATENT OFFICE

164,064

COMBINED CANDLEHOLDER AND PLANTER OR SIMILAR ARTICLE

Edmund Rubel, New York, N. Y.

Application June 17, 1950, Serial No. 10,611.

Term of patent 3½ years

(Cl. D48—2)

To all whom it may concern:

Be it known that I, Edmund Rubel, a citizen of the United States, residing at the city of New York, Borough of Manhattan, in the county of New York and the State of New York, have invented a new, original, and ornamental Design for a Combined Candleholder and Planter or Similar Article, of which the following is a specification, reference being had to the accompanying drawing, forming a part hereof.

In the drawing:

Fig. 1 is a front elevational view of a combined candleholder and planter or similar article, showing my new design;

Fig. 2 is a cross sectional view thereof taken on the line 2—2 of Fig. 1; and

Fig. 3 is a rear elevational view.

The broken lines shown in the drawing are for illustrative purposes only.

I claim:

The ornamental design for a combined candleholder and planter or similar article, substantially as shown and described.

EDMUND RUBEL.
